LATCH FOR VERTICAL STORAGE
FILING CABINETGraham Irving Barker, 208 Golden Oaks, Corlett Drive,
Johannesburg, Transvaal, Republic of South Africa
Filed Dec. 1, 1965, Ser. No. 511,295
3 Claims. (Cl. 312—184)

This invention relates to filing cabinets for drawings and the like in which the drawings are hung vertically on pins projecting from moving laths, and more particularly to the mechanism for limiting the movement of said laths.

It is a primary object of the invention to provide an improved latch arrangement for stopping a movable lath in an intermediate partially open position in which access to the stored articles is provided without full disengagement of the pins therefrom. Another object is to provide such a latch member capable of selectively stopping the movable lath in either of its intermediate or fully opened positions.

In general the invention features a stop member mounted on the movable lath and a manually operable spring biased latch mounted on the cabinet frame adjacent the movable lath for pivotal movement toward and away from the stop member, the latch having an edge adjacent the stop running parallel to the direction of motion of the lath and a slot in the edge for receiving the stop when the lath is in the desired intermediate position. In preferred embodiments a rear stop surface on the latch cooperates with the stop member to lock the lath in its fully open position.

Other objects, features, and advantages will appear from the following description of a preferred embodiment of the invention, taken together with the attached drawings thereof, in which:

FIG. 1 is a plan view of a cabinet;

FIG. 2 is an enlarged plan view of a portion of the cabinet;

FIG. 3 is a section along 3—3 of FIG. 2; and

FIG. 4 is a section along 4—4 of FIG. 3.

Referring to the drawings, a vertical storage filing cabinet 10 is provided with a plurality of laths 20 movable on bearings such as rollers 12 in tracks 14 in the cabinet frame 11. Shaft 15 is connected to sprockets 16 coacting with chain members 18 to maintain the parallel relationship of the laths 20 as they are moved. Interspersed horizontal pins 22, 24 mounted on the opposing faces of the laths 20 are provided to support stored material.

Each lath 20 is movable between a fully closed position in which the free ends 23 of its pins are adjacent the mounted ends 21 of the pins on the opposite lath, and a fully opened position in which ends 23 are withdrawn beyond free ends 23 of the pins on the opposite lath.

Bracket 30 is mounted on top of frame 11 over track 14 adjacent the path of a lath 20. Latch 32, having generally horizontal portion 34 and vertical portion 36 directed laterally inwardly toward the lath, is mounted in bracket 30 on shaft 31 for pivotal movement toward and away from the lath. Control shaft 40 is mounted on portion 34 and extends through elongated slot 42 in bracket 30, terminating in knob 44. Spring 46 around shaft 40 bears against bracket 30 and portion 34 to bias the latch toward the lath.

Vertical stop member 48 is mounted on the rear of lath 20 and extends up to intersect lower horizontal edge 38 of latch portion 36, acting against spring 46 to raise the latch away from the lath. Slot 50 in edge 38

2

receives stop 48 when the lath is in an intermediate position between its fully closed and fully opened positions with the pins 22, 24 still partially overlapping. In this position access to the stored articles is provided without the necessity of disengaging them fully from the pins. When the stop and slot are aligned, spring 46 presses the slot over the stop to lock the lath in its intermediate position. Rear vertical stop surface 52 of the latch cooperates similarly with the stop 48 to lock the lath in its fully opened position. The lath can be unlocked from its fully opened or intermediate positions by moving knob 44 laterally outwardly away from the lath. Stop 48 rides against edge 38 while the latch moves between its positions.

Other embodiments will occur to those skilled in the art and are within the following claims.

What is claimed is:

1. In a filing cabinet having a frame and at least one pair of cooperating laths each having mounted thereon a multiplicity of pins, said pins on each of said laths being directed toward and interspersed between the pins on the other said lath, at least one of said laths being movable toward and away from the other said lath between a fully closed position in which the free ends of its said pins are adjacent the mounted ends of the pins on the other lath, and a fully opened position in which said free ends are withdrawn beyond the free ends of the pins on the other lath, that improvement comprising a stop member mounted on said movable lath, a manually operable latch mounted on said frame adjacent said movable lath for pivotal movement toward and away from said stop member, said latch having an edge adjacent said stop running parallel to the direction of motion of said movable lath and a slot in said edge for receiving said stop member located so that when said stop member is in said slot said movable lath is in an intermediate partially closed position between said fully opened and fully closed position, whereby access to the stored articles is provided without disengaging the pins fully therefrom, and a spring biasing latch toward said stop member with said edge riding against said stop member when said lath is between said positions and locking said stop member in said slot when said lath is in said intermediate position.
2. The improvement of claim 1 wherein said latch has a rear stop surface extending upwardly from said edge and located so that said stop member moves across said edge adjacent said surface when said lath is in its fully opened position.
3. The improvement of claim 1 wherein said latch is pivotally mounted in a bracket and comprises a generally horizontal portion, a vertical portion extending downwardly therefrom adjacent said lath, said edge being the lower edge of said vertical portion, and a control shaft extending up from said horizontal portion through an elongated slot in said bracket, said spring surrounding said shaft between said horizontal portion and said bracket.

UNITED STATES PATENT OFFICE
CERTIFICATE OF CORRECTION

Patent No. 3,312,514

April 4, 1967

Graham Irving Barker

It is hereby certified that error appears in the above numbered patent requiring correction and that the said Letters Patent should read as corrected below.

Column 1, line 24, for "latch" read -- lath --; column 2, line 9, for "is" read -- its --; line 44, after "biasing" insert -- said --.

Signed and sealed this 28th day of November 1967.
